UNITED STATES PATENT OFFICE.

MARVIN B. VAN NESS, OF WELSH, LOUISIANA.

CENTRIFUGAL PUMPING MECHANISM.

1,108,089.

Specification of Letters Patent. Patented Aug. 18, 1914.

Application filed February 16, 1912. Serial No. 677,894.

To all whom it may concern:

Be it known that I, MARVIN B. VAN NESS, residing at Welsh, in the parish of Calcasieu and State of Louisiana, have invented certain new and useful Improvements in Centrifugal Pumping Mechanism, of which the following is a specification.

My invention relates to certain new and useful improvements in centrifugal pumping mechanism for wells, and the invention has for one of its objects to provide means for strengthening the connection between the driving pulley and the line shaft, whereby the pull of the driving belt will not buckle the line shaft.

Another object of the invention is to provide means whereby the line shaft and the shaft casing with its bearings may be pulled under strain into perfect alignment to prevent undue friction in the bearings due to uneven alignment.

A third object of the invention is to provide an improved means for sealing the suction pipe of the pumping mechanism in the well; and a fourth object of the invention, is to so construct and design the various parts of the mechanism as to render the operation of the pump more efficient than heretofore.

In addition to providing means for accomplishing the foregoing objects, the invention also resides in the provision of those novel details of construction, combination and arrangement of parts, all of which will be first fully described, and then be specifically pointed out in the appended claims, reference being had to the accompanying drawings, in which:

Figure 1, is a central longitudinal vertical section of the upper part of the pumping mechanism. Fig. 2, is a view similar to Fig. 1 of the lower part of the mechanism, showing the pump and the suction pipe with the sealing mechanism that cooperates with the suction pipe. Fig. 3 is a cross section on the line 3—3 of Fig. 1. Fig. 4 is a cross section on the line 4—4 of Fig. 1. Fig. 5 is a detail section on the line 5—5 of Fig. 2.

In the drawings in which like numerals and letters of reference indicate like parts in all of the figures, 1 is the pit or well casting, which may be of the ordinary construction, and which, at the top receives the pit top 2.

3 is the pump head which is secured to the pit top 2, as at 4, the pump head 3 having

an internal thread 5 at its lower end to receive the water pipe 6. The pipe 6 may be made either in a single length or in sections joined together as at 7, depending on the depth of the well, and as may be made necessary by the requirements of the particular well in which the mechanism is to be employed.

9 is the outlet pipe for the water which is joined at 10 over the discharge opening 8, of the pump head 3.

15 designates the pump casing which in the present form of the invention is of the duplex type and has its ends closed by the caps 13 and 16, which are secured at 14 and 17, respectively to the casing 15. To the upper cap 13, the union 11 that receives the lower end of the water pipe 6, is fastened as at 12 so as to bring the pipe 6 in connection with the interior of the casing 15. The suction pipe 19 is connected to the casing 15 through the medium of the union 18. The pump casing 15 incloses the partitions which carry the shaft bearings 20 and 21 respectively, and also inclose the impellers 23.

The construction of the pump (i. e. the parts which include the casing 15 and its internal parts) may be of any approved construction, as the same *per se* forms no part of the present invention.

24 is the lower thrust bearing which is secured to the shaft 22, it being of course understood that when the water pipe 6, and the shaft casing 44, are made in sections, the shaft 22 would also be made in sections, coupled together by a sleeve 25, as is the usual practice. The shaft 22, at its upper end, has a feather slot or groove 26 in which the key or feather 36 of the driving pulley 35 lies, and with which the set screw 29 of the adjusting nut 28 cooperates. The adjusting nut 28 has each face tapped at 30 to receive the set screw 29, whereby minute adjustments may be made, and the set screw 100 always enters into the groove 26 to assure non-slipping of the adjusting nut, it being understood of course that the upper end of the shaft 22 will be threaded as at 27 to receive the nut 28.

31 is the main bearing member that fits on the pump head 3 and supports the line shaft 22 and the impellers 23. The bearing 31 is pocketed and bushed with bearing metal as at 33 to receive the long hub 34 of the pulley 35.

37 is the upper ball race member that

turns with the head 34 and between which and the lower ball race member 38, the anti-friction bearings 40, are located, the members 37, 38 and 40 acting as a thrust bearing for the shaft 22. Below the web 39 of the bearing member 31, the said member is counter-bored as at 41 and tapped as at 42 to receive the upper end of the shaft casing 44 which is threaded at 43 to coöperate with the threads 42.

10 The shaft casing consists of a plurality of tubes 44 which are joined to bearings 45 by collars 46, the collars 46 being spaced apart to retain the spider 47 which is swivelly mounted on the bearing 45 and rests snugly in (but is not secured to) the inside of the water pipe 6. The bearing members 45 have upwardly projecting sleeves 48 to form pockets 49 to collect any sediment that may 15 accumulate in the pipe 44 and prevent it working into the bearing face of the respective bearing member 45. The lower shaft case section 44 is secured to the upper bearing member 21 of the pump at 56 through 20 the medium of a reducing joint 57, as best indicated in Fig. 2 of the drawings.

25 The bearing member 31 has a water chamber 32 that is provided with an inlet 50 and a water outlet 51 whereby the water of the well may circulate around the bearing proper of the bearing member 31 and keep the same cool. The bearing member 31 may also be provided with an oil duct 52 into which oil may be conveyed from a suitable 30 reservoir, not shown, through a pipe 53, if desired.

58 designates the strainer pipe into which the suction pipe 19, projects.

60 is the seal which effects a snug joint 40 between the pipes 19 and 58, and the seal 60 is in the nature of a collar, which slides on a pipe 19, and has its lower face coniformed to project into the pipe 58. In 45 order to assist in forming a tight seal and also to support the strainer pipe, it may be provided at its upper end with a collar 59 having lugs 62 to enter bayonet slots 65, in the body 64 of the pit bottom member 63, as best shown in Fig. 2 of the drawings.

50 In putting the pump in the well, the well pit is of course first placed into position, and the strainer pipe likewise. The pump casing and its carried parts, the suction pipe 19, the water pipe 6, the line shaft and the 55 shaft casing are all assembled together with the pump head and pit top before being lowered into the well. After they are lowered into the well, the bearing member 31 is put into place and screwed to the upper 60 pipe section 44. By applying a pipe wrench to the bearing member 31 and turning it, tension can be put on the shaft casing 44 to draw it into absolutely true alinement and thereby aline all of the bearings 45 (the 65 number of which will depend on the depth

of the well) so that the shaft 22 will not bind in the said bearings. After the required tension has been applied to the casing 44, the bearing member 31 is bolted down by the bolts 55 to the pump head. 70 The pulley 35 is slipped into place and the impellers 23 properly adjusted by the nut 28. The pump is then ready for operation, it being understood of course that the seal 60 is held on the pipe, and when the said pipe is lowered into place, it effectively seals the connection between the suction pipe 19 and the strainer pipe 58.

75 In operation, power is applied to the pulley 35 to turn the shaft 22, thereby setting 80 the impellers 23 into operation, to suck the water up the pipe 19, pass it through the pump casing 15 and force it upwardly through the water pipe 6 in the duct formed between such pipe and shaft casing 44, out 85 through the outlet 9. The water comes in practically direct contact with the bearings 45 and collars 46 and thus insures the proper cooling of the bearings 45, while the water in the chamber 32 will insure proper cool- 90 ing of the bearing 33 at all times.

95 From the foregoing, it will be observed, by my present construction, a more efficient pump is contained than heretofore, and the parts are so combined and designed that with a minimum effort in the assembling of the parts, and at any other time when necessary, absolute alinement of the various 100 bearings 45 can be had by simply tightening up the connection between the upper section 44 of the shaft casing and the bearing member 31.

105 From the foregoing description taken in connection with the accompanying drawings, it is believed the complete construction, operation, and advantages, of the invention will be apparent to those skilled in the art to which it appertains.

What I claim is:—

110 1. The combination with the pump casing, the impeller therein, a shaft bearing carried by the pump casing, a line shaft passing through said bearing and carrying said impeller, a pump head, means for forming a water conduit for suspending said pump casing from said pump head, a head bearing member through which said line shaft projects, said head bearing member being mounted on said pump head, a set of line shaft bearings between said head bearing member and said pump casing member, and means connecting all of said bearing members together, and having provisions in virtue of which as said head bearing member is turned on said pump head, all of said bearing members will be put under tension and drawn into alinement, and a driving pulley on said line shaft.

115 2. In a pumping mechanism, the combination with the pump casing, the impeller 120

- mounted therein and the pump casing line shaft bearing, of a pump head and a pipe connecting said pump head with said pump casing for suspending the same and forming
- 5 a water conduit, a head bearing member mounted on said pump head, a line shaft passing through said bearing members and carrying said impeller, an intermediate shaft bearing between said pump casing
- 10 bearing and said head bearing member, a pipe embracing said line shaft and rigidly connected to said pump casing bearing and to said intermediate bearing, a second pipe connected to said intermediate bearing and
- 15 to said head bearing, the connection between said head bearing and said pipe being such that as said head bearing is turned, said pipes that embrace said line shaft and said intermediate bearing, will be put under tension to bring all of said bearings into alignment, substantially as shown and described.
3. In a pump of the character described, a pump casing, an impeller operating therein, a line shaft bearing carried by said casing, a pump head, means for rigidly suspending said pump casing from said pump head, to maintain said pump casing immovable with relation to said pump head, a head bearing member mounted on said pump
- 25 head, a line shaft passing through said head bearing member and through said pump casing bearing member and carrying said impeller, means for driving said line shaft, an intermediate line shaft bearing between
- 30 said head bearing and said pump casing bearing, a pipe rigidly connected at one end with said intermediate bearing and rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to
- 35 said pipes and said intermediate bearing to align said intermediate bearing with said head bearing and with said pump casing bearing, substantially as shown and for the purposes described.
- 40 4. In a pump of the character described, a pump casing, an impeller operating therein, a line shaft bearing carried by said casing, a pump head, means for rigidly suspending said pump casing from said pump head to maintain said pump casing immovable with relation to said pump head, a head bearing member mounted on said pump head, a line shaft passing through said head bearing member and through said
- 45 pump casing bearing member and carrying said impeller, means for driving said line shaft, an intermediate line shaft bearing between
- 50 said head bearing and said pump casing bearing, a pipe rigidly connected at one end with said intermediate bearing and rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to
- 55 said pipes and said intermediate bearing to align said intermediate bearing with said head bearing and with said pump casing bearing, substantially as shown and for the purposes described.
- 60 5. In a pump of the character described, a pump casing, an impeller operating therein, a line shaft bearing carried by said casing, a pump head, means for rigidly suspending said pump casing from said pump head to maintain said pump casing immovable with relation to said pump head, a head bearing member mounted on said pump head, a line shaft passing through said head bearing member and through said
- 65 pump casing bearing member and carrying said impeller, means for driving said line shaft, an intermediate line shaft bearing between said head bearing and said pump casing bearing, a pipe rigidly connected at one end with said intermediate bearing and
- 70 rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to said pipes and said intermediate bearing to align said intermediate bearing with said head bearing and with said pump casing bearing, said head bearing member having a bearing pocket, said shaft driving means including a pulley having a bearing hub mounted in said pocket and thrust bearings interposed between said hub and said head bearing member to sustain the thrust of said line shaft and its carried parts.
- 75 6. In a pump of the character described, a pump casing, an impeller operating therein, a line shaft bearing carried by said casing, a pump head, means for rigidly suspending said pump casing from said pump head to maintain said pump casing immovable with relation to said pump head, a head bearing member mounted on said pump head, a line shaft passing through said head bearing member and through said pump casing bearing member and carrying said impeller, means for driving said line shaft, an intermediate line shaft bearing between
- 80 said head bearing and said pump casing bearing, a pipe rigidly connected at one end with said intermediate bearing and rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to
- 85 said pipes and said intermediate bearing to align said intermediate bearing with said head bearing and with said pump casing bearing, said head bearing member having a bearing pocket, said shaft driving means including a pulley having a bearing hub mounted in said pocket and thrust bearings interposed between said hub and said head bearing member to sustain the thrust of said line shaft and its carried parts.
- 90 7. In a pump of the character described, a pump casing, an impeller operating therein, a line shaft bearing carried by said casing, a pump head, means for rigidly suspending said pump casing from said pump head to maintain said pump casing immovable with relation to said pump head, a head bearing member mounted on said pump head, a line shaft passing through said head bearing member and through said pump casing bearing member and carrying said impeller, means for driving said line shaft, an intermediate line shaft bearing between
- 95 said head bearing and said pump casing bearing, a pipe rigidly connected at one end with said intermediate bearing and rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to
- 100 said pipes and said intermediate bearing to align said intermediate bearing with said head bearing and with said pump casing bearing, said head bearing member having a bearing pocket, said shaft driving means including a pulley having a bearing hub mounted in said pocket and thrust bearings interposed between said hub and said head bearing member to sustain the thrust of said line shaft and its carried parts.
- 105 8. In a pump of the character described, a pump casing, an impeller operating therein, a line shaft bearing carried by said casing, a pump head, means for rigidly suspending said pump casing from said pump head to maintain said pump casing immovable with relation to said pump head, a head bearing member mounted on said pump head, a line shaft passing through said head bearing member and through said pump casing bearing member and carrying said impeller, means for driving said line shaft, an intermediate line shaft bearing between
- 110 said head bearing and said pump casing bearing, a pipe rigidly connected at one end with said intermediate bearing and rigidly connected at its other end with said pump casing bearing, another pipe rigidly connected with said intermediate bearing, and means co-operatively connecting said other pipe with said head bearing, in virtue of which when said head bearing is turned on said pump head, tension will be applied to
- 115 said pipes and said intermediate bearing to align said intermediate bearing with said head bearing and with said pump casing bearing, said head bearing member having a bearing pocket, said shaft driving means including a pulley having a bearing hub mounted in said pocket and thrust bearings interposed between said hub and said head bearing member to sustain the thrust of said line shaft and its carried parts, said line shaft having a key groove, and said pulley having a key for entering said groove, said line shaft having a threaded portion, and a nut threaded on said threaded portion to engage said pulley for adjusting said line
- 120 shaft to adjust said impeller, said nut having a plurality of faces provided with tapped apertures, and a set screw adapted to pass through said apertures and project into said key groove to hold said nut from
- 125 turning.
9. In a pump mechanism, a pit top, a pump head mounted on said pit top, a pump casing, a water pipe connecting said pump head with said casing to suspend the said

casing, an impeller operating in said casing, a line shaft bearing carried by said casing, a head bearing mounted on said pump head, a sectional shaft 5 casing rigidly secured at one end to said pump casing bearing and adjustably secured at its other end to said head bearing, whereby when said head bearing is turned, said sectional shaft casing will be 10 put under tension, said sectional shaft casing including a bearing section, and a line shaft projecting through all of said bearings and carrying said impeller, and a spider swivelly mounted on said bearing section 15 and having arms engaging the internal wall of said first mentioned pump casing suspending pipe, said head bearing member having a deep bearing pocket and a driving pulley having a bearing hub mounted in said 20 pocket and secured to said shaft, in virtue of which said shaft may be driven.

7. In a pumping mechanism the combination with the pump casing, the pump head and the water pipe connecting said casing of 25 the pump with said head, the impeller and the line shaft, of a head bearing mounted on said pump head and having a passage through which said line shaft projects, said head bearing having an elongated bearing 30 pocket, a pulley having an elongated bearing hub mounted in said pocket and connected to said shaft to turn the same, a thrust bearing in said pocket for said pulley hub, and a water cooling jacket surrounding said elongated bearing pocket and means for effecting 35 a circulation of water through said jacket.

8. In a pumping mechanism the combination with the pump casing, the pump head 40 and the water pipe connecting said casing of the pump with said head, the impeller and the line shaft, of a head bearing mounted on said pump head and having a passage through which said line shaft projects, said head bearing having an elongated bearing 45 pocket, a pulley having an elongated bearing hub mounted in said pocket and connected to said shaft to turn the same, a thrust bearing in said pocket for said pulley hub, and a water cooling jacket surrounding 50 said elongated bearing pocket and means for effecting a circulation of water through said jacket, an intermediate line shaft bearing member, a spider swivelly mounted on said 55 intermediate member and located in said pump casing suspending pipe, collars on said intermediate bearing member for retaining said spider on the same, and means for holding said intermediate bearing member in position on the shaft.

9. In a pumping mechanism the combination with the pump casing, the pump head and the water pipe connecting said casing of the pump with said head, the impeller 65 and the line shaft, a head bearing mounted

on said pump head and having a passage through which said line shaft projects, said head bearing having an elongated bearing pocket, a pulley having an elongated bearing hub mounted in said pocket and connected 70 to said shaft to turn the same, a thrust bearing in said pocket for said pulley hub, and a water cooling jacket surrounding said elongated bearing pocket and means for effecting a circulation of water through said 75 jacket, an intermediate line shaft bearing member, a spider swivelly mounted on said intermediate member and located in said pump casing suspending pipe, collars on said intermediate bearing member for retaining 80 said spider on the same, and means for holding said intermediate bearing member in position on the shaft, and coöperating with said head bearing member for maintaining said intermediate bearing in alinement with 85 said pump casing bearing member and with said head bearing.

10. In a pumping mechanism a pump head, a pump casing, a water duct uniting said pump head to said pump casing, an impeller in said pump casing, a line shaft passing through said pump head and said duct into said pump casing to carry said impeller, a head bearing member mounted on said pump head and including an elongated 90 bearing chamber, a pulley having an elongated hub mounted in said bearing chamber, said head bearing projecting into said pulley, said head bearing including a water jacket spaced around said elongated bearing 95 chamber, and also including a lubricant conveying duct for delivering lubricant into said elongated bearing chamber, and a thrust bearing mounted in said chamber to support said pulley and shaft. 100

11. In a pumping mechanism a pump head, a pump casing, a water duct uniting said pump head to said pump casing, an impeller in said pump casing, a line shaft passing through said pump head and said duct 110 into said pump casing to carry said impeller, a head bearing member mounted on said pump head and including an elongated bearing chamber, a pulley having an elongated hub mounted in said bearing chamber, said 115 head bearing projecting into said pulley, said head bearing including a water jacket spaced around said elongated bearing chamber, and also including a lubricant conveying duct for delivering lubricant into said elongated bearing chamber, and a thrust bearing mounted in said chamber to support said pulley and shaft, said head bearing member including a portion projecting into said 120 pump head, and a shaft casing inclosing said 125 shaft and connected with said head bearing projecting portion and with said pump casing, substantially as shown and described.

12. In a pumping mechanism a pump head, a pump casing, a water duct uniting 130

said pump head to said pump casing, an impeller in said pump casing, a line shaft passing through said pump head and said duct into said pump casing to carry said impeller, 5 a head bearing mounted on said pump head and including an elongated bearing chamber, a pulley having an elongated hub mounted in said bearing chamber, said head bearing projecting into said pulley, said 10 head bearing including a water jacket spaced around said elongated bearing chamber, and also including a lubricant conveying duct for delivering lubricant into said elongated bearing chamber, and a thrust bearing 15 mounted in said chamber to support said pulley and shaft, said head bearing member including a portion projecting into said pump head, and a shaft casing inclosing said shaft and connected with said head bearing 20 projecting portion and with said pump casing, said shaft casing including a plurality of pipe sections and interposed bearing sections, collars uniting said bearing sections with the respective pipe sections, and a 25 spider swivelly mounted on the respective bearing sections, between the collars thereof.

13. In a pumping mechanism a pump head, a pump casing, a water duct uniting said pump head to said pump casing, an impeller in said pump casing, a line shaft passing through said pump head and said duct into said pump casing to carry said impeller, a head bearing member mounted on said pump head and including an elongated bearing 30 chamber, a pulley having an elongated hub mounted in said bearing chamber, said head bearing projecting into said pulley, said head bearing including a water jacket spaced around said elongated bearing chamber, and also including a lubricant conveying duct for delivering lubricant into said elongated bearing chamber, and a thrust bearing mounted in said chamber to support said pulley and shaft, said head bearing member including a portion projecting into 35 said pump head, and a shaft casing inclosing said shaft and connected with said head bearing projecting portion and with said pump casing, said shaft casing including a plurality of pipe sections and interposed bearing sections, collars uniting said bearing sections with the respective pipe sections, and a spider swivelly mounted on the respective bearing sections, between the collars thereof, said pipe casing bearing sections including sleeves projecting upwardly around said shaft into the adjacent shaft casing section and of less diameter than the same to leave a sediment collecting pocket, 50 substantially as shown and described.

14. In a pumping mechanism a pump casing or pit, a pit top and a pit bottom, a centrifugal pump suspended from said pit top and including a suction pipe projecting

through said pit bottom, a strainer pipe supported from said pit bottom, said suction pipe extending into said strainer pipe, and a well seal slidably mounted on said suction pipe for projecting into the end of said strainer pipe to seal the connection between 65 said strainer pipe and said suction pipe, said strainer pipe having a collar provided with lugs, and said pit bottom having a member provided with a bayonet slot to receive said lugs, substantially as specified. 70

15. In a pumping mechanism, the combination with the well pit, the pit top and the pit bottom, of a pump mounted in the casing and including a pump head, a pump casing suspended from the pump head, a line 80 shaft passing through said pump head into said pit casing and into said pump casing, an impeller in said pump casing, a suction pipe communicating with said pump casing, a pipe beneath said pump casing into which 85 said suction pipe projects, and a gravity set well seal slidably mounted on said suction pipe to engage said pipe into which said suction pipe projects and effect a sealing connection between the same. 90

16. In a pumping mechanism, a head bearing for the line shaft, said head bearing being adapted to be mounted on the pump head and having a passage through which the line shaft projects, said head bearing 95 having a pocket, a pulley having a hub projected into and having bearing relation with said pocket, and a thrust bearing for the pulley hub mounted in said pocket, and means for applying a cooling agent around 100 said pocket to cool the bearing.

17. In a pumping mechanism the combination with the pump casing, the pump head and the water pipe connecting said pump casing with said head, the impeller and the line shaft, of a head bearing mounted on said pump head and having a passage through which said line shaft projects, said head bearing having an elongated bearing space, a pulley having an elongated bearing 110 hub mounted in said space and connected to said shaft to turn the same, a thrust bearing for said pulley hub, said thrust bearing and hub being contained in the same chamber, and a water cooling jacket surrounding said 115 elongated bearing space and means for effecting a circulation of water through said jacket.

18. In a pumping mechanism the combination with a pump head, of a pump casing, a water duct connecting said pump head to said pump casing, an impeller in said pump casing, a line shaft passing through said pump head and said duct into said pump casing to carry said impeller, a head bearing member mounted on said pump head and including an elongated bearing, a pulley having an elongated hub mounted in said

120
125

bearing, said head bearing projecting into said pulley, a thrust bearing mounted to support said pulley and shaft, said thrust bearing and hub being contained in the same chamber, said head bearing including a water jacket spaced around said elongated bearing, and also including a lubricant con-

veying duct for delivering lubricant into said chamber.
